2 SHEETS-SHEET 2

UNITED STATES PATENT OFFICE.

NICHOLAS REMMEL, OF KEWASKUM, WISCONSIN, ASSIGNOR TO REMMEL MANUFACTURING COMPANY, OF KEWASKUM, WISCONSIN.

CONCRETE MIXER.

Application filed March 1, 1920. Serial No. 362,371.

To all whom it may concern:

Be it known that I, NICHOLAS REMMEL, a citizen of the United States, and resident of Kewaskum, in the county of Washington and State of Wisconsin, have invented certain new and useful Improvements in Concrete Mixers; and I do hereby declare that the following is a full, clear, and exact description thereof.

10 My invention pertains to new and useful improvements in mixing machines, particularly those which are used for mixing batches of concrete.

The primary object of my invention is to 15 provide a continuously drum driven concrete mixer which is perfectly balanced with reference to its load and fulcrum point and which is capable of being adjusted to various angles during a mixing operation and also 20 tilttable in two directions from a vertical line for discharging.

Another object of my invention is to provide a driving gear connection for the drum whereby a power belt is directed parallel to 25 the pivotal point of the axis, whereby clearance is obtained to permit free dumping of the concrete in two directions with relation to the frame without interference from the driving belt or its gear connections.

30 Another object of my invention is to provide a single lever for oscillating the drum associated with means for locking the drum at predetermined angles upon either side of a vertical line from the axis of the drum.

35 A further object of my invention is to provide a simple, economical and effective train of gear connections between the power pulley and revolvable axis of the drum, whereby perfect balance is maintained and 40 manufacturing cost is reduced to a minimum.

With the above and other objects in view the invention consists in certain peculiarities of construction and combination of parts as 45 are herein set forth with reference to the accompanying drawings and subsequent claims.

In the drawings:

Figure 1 represents a side elevation of a 50 concrete mixing drum exemplifying the features of my invention, with parts broken away and in section, to more clearly illustrate certain details of construction.

Figure 2 is a plan view of the same with

parts broken away and in section, to more 55 clearly show the driving gear connection for revolving the drum.

Figure 3 represents an end elevation of the drum with parts broken away, the side elevation showing the means for manipulating the drum about its swinging axis and for locking the said drum at predetermined angles, and

Figure 4 is a detailed cross sectional view upon a slightly larger scale of the means for 65 adjusting the drum locking mechanism.

Referring by characters to the drawings, 1 represents the side struts of a frame, to the upper end of which struts is secured a reach bar 2, the same being cross connected to the 70 struts by tie bars 3.

As best shown in Figures 1 and 2, the reach bar at one end is formed with a sleeve 4 having journaled thereon a counter-shaft 5 to which is secured a power pulley 6 and at 75 the other end of this shaft is secured a bevelled gear 7. The bevelled gear 7 is meshed with a corresponding bevelled gear 8 which bevelled gear is formed integrally with the spur gear 9. The combined bevelled and 80 spur gear is loosely mounted upon a journaled stud 10, which stud is supported in bosses upon opposite sides of the gear, the outer boss constituting the terminal of a U shaped bracket 11, which springs from the 85 sleeve 4 of the reach bar.

A corresponding pintle stud 10' is supported by a boss 12 which also forms a part of the reach bar at its opposite end, this pintle stud being in axial alignment with the 90 pintle stud 10. The inner ends of the pintle studs 10 and 10' constitute oscillatory bearings for the upturned ends 13' of a drum carrying yoke 14. The upturned end 13 of the yoke is formed with a journaled box 15 for an arbor 16, which arbor is positioned parallel to the pintle studs 10 and 10'. The arbor 16 has secured to its outer end a spur gear 9' which meshes with the spur gear 9 and the inner end of the arbor carries a 100 bevelled pinion 17, it being understood, that the inner end of the arbor has a bearing in a box 15' that springs from the body portion of the drum yoke 14.

The drum yoke 14 is formed with a vertical and centrally disposed journal box 18 for the reception of a spindle 19. The upper end of the spindle 19 is fastened within a

2
hub 20, which hub constitutes a part of a circular bottom casting 21 of a mixing drum, the cylindrical side walls 22 of which are secured to the bottom casting 21 in any suitable manner.

Forming an integral part of the bottom casting 21 is a bevelled gear wheel 23, which gear wheel meshes with the bevelled pinion 17 whereby rotary motion is imparted to the drum, it being understood that said drum has an open mouth and is adapted to be revolved to effect a proper mixture of the concrete batch. To insure an efficient mixture of the materials the inner walls 22 of the drum are provided with blades 22', as best shown in Figures 1 and 2.

In order to manually swing the mixing drum about its pintle axis, I provide a hand lever 23' having bowed terminals 23'' which are in pivoted union with the lower portion of the yoke leg 13'. This lever is also provided with a centrally disposed tooth 24, which tooth is adapted to enter a slot 25, that is formed in an adjustable block 25', whereby upon swinging the lever in one direction, when the tooth is in alignment with the slot 25, the yoke together with the mixing drum is locked at a predetermined angle during a concrete mixing operation. The block 25', as best shown in Figures 3 and 4, is mounted between ribs 26 of a circular support 27, which detent is bolted or otherwise secured to the upper portion of the reach bar 2 and surrounding its boss 12, as best shown in Figure 3, the detent is formed with oppositely disposed circular slots 27' through which a retaining bolt 28 is fitted for the purpose of adjusting and locking the block 25'. For example, if it is desired to operate the drum from the right hand side, as shown in Figure 3, the block is fitted to the detent upon that side of the same, and adjusted so as to lock the drum at a predetermined angle and when the concrete mixture or batch is completed, the hand lever 23 is manipulated so as to release the drum from its angular position whereby the contents of said drum may be

dumped by swinging the same down to a discharging position.

Should it be desired to operate the drum upon the left hand side, as indicated at the dotted line X, the block is shifted to the opposite side of the detent and the same operation with reference to locking and swinging the drum is effected. This change of direction in dumping the drum contents is desirable in some instances where the machine is in operation close to a wall, or where other conditions exist that would make it desirable to work from one side or the other, as for example, in some instances it may be desired to dump the batch upon one side of the frame and then when the drum is locked for a second batch, during the interval of mixing, it can be swung over to the other side of the frame and dumped in the opposite direction. Under these conditions the batches are discharged from opposite sides and time may be saved thereby.

While I have shown and described only one exemplification of my invention in all its details, it is understood that I may vary such details within the scope of the claim.

I claim:

The combination of a reach bar, a pair of alined pivots carried thereby, a yoke rotatable on said pivots, a drum rotatable on said yoke, means for rotating said drum, a lever having bowed terminals thereon at their lower ends to said yoke, a tooth carried by said lever, a support on said reach bar having an arcuate slot therein, a block, means securing said block in said slot, said means being releasable to permit adjustment of said block in said slot, said block having a groove therein whereby on the movement of said lever and the rotation of said yoke, said tooth may be inserted into said groove for locking said drum in tilted position.

In testimony that I claim the foregoing I have hereunto set my hand at Kewaskum, in the county of Washington and State of Wisconsin.

NICHOLAS REMMEL.
